UNITED STATES PATENT OFFICE.

STEPHEN A. HASBROUCK, OF NEW HAVEN, CONNECTICUT.

FUEL INJECTOR.

1,418,566.

Specification of Letters Patent. Patented June 6, 1922.

Application filed May 1, 1919. Serial No. 294,010.

To all whom it may concern:

Be it known that I, STEPHEN A. HASBROUCK, a citizen of the United States, residing at New Haven, in the county of New Haven and State of Connecticut, have invented certain new and useful Improvements in Fuel Injectors, of which the following is a specification, reference being had thereto to the accompanying drawings.

10 This invention relates to new and useful improvements in fuel injectors, having more particular reference to means for admitting liquid fuel into the cylinder of an internal combustion engine.

15 It is the object of this invention, among other things, to provide means whereby the fuel may be injected into the cylinder in a spray or mist of maximum area by mechanism that is simple to operate and will permit the starting of the engine at a low pressure and when cold.

20 To these, and other ends, my invention consists in the fuel injector, having certain details of construction and combinations of 25 parts, as will be hereinafter described and more particularly pointed out in the claims.

25 Referring to the drawings, in which like numerals of reference designate like parts in the several figures;

30 Figure 1 is a sectional elevation of an internal combustion engine having my new and improved device connected therewith;

Figure 2 is an enlarged detail view of a modified form of inlet plug; and

35 Figure 3 is an enlarged fragmentary view of the parts adjacent to the valve and its seat.

40 In the drawings and description herein the improvement is shown and described as applied to a single cylinder engine but it may be used with equal advantage in multiple cylinder engines.

45 This invention has advantageously been combined with the fuel pump, thereby eliminating many parts and very materially simplifying the device thereby.

50 In the drawings, the numeral 1 designates the frame of an internal combustion engine, and 2 the cylinder thereof, within which the piston 3 is operated from a crank shaft 4, through the piston rod 5, and projecting through one side of the cylinder is a spark plug 6.

55 The form and structure of the engine itself is not material to this invention and the one illustrated is merely adopted as a convenient type thereof.

Threaded into the upper end of the cylinder 2 is the inlet plug 7 having a chamber 8 therein which is closed at one end by a plug 9 and extending from said chamber to the bottom of the plug is a port 10, which terminates at its bottom end in the flaring valve seat 11.

Operatively mounted within said plug is the valve stem 12 having a globular valve 13 at one end and a spring 14 surrounding it, which abuts against one wall of the chamber 8 and against a collar 15 fixed on the valve stem 12.

70 Secured to the engine is a frame 16 having a cylinder 17 forming a part thereof and in which is the chamber 18 that opens into a port 19 connected at one end with an inlet pipe 20 and at the other end with a conductor pipe 21, and having check valves 22 and 23 mounted therein. The conductor pipe 21 is connected at its other end to the inlet plug 7 whereby a fluid passing therethrough may enter the chamber 8.

75 Reciprocating within the cylinder 17 is a plunger 24 having a head 25 thereon and a collar 26 at one end thereof with a spring 27 surrounding it and exerting its tension so as to move the plunger 24 upwardly, 80 which upward movement is limited by a lever 28 hinged to the frame at 29 and adjusted relatively to said frame by means of nuts 30 upon a stud 31 secured in said frame and a spring 32 that normally holds the outer end of the lever 28 in its up position.

85 An impact mechanism is utilized to move the plunger in one direction and comprises a hammer 33 mounted upon a shaft 34 supported in lugs 35 integral with the frame 16, 90 a dog 36 also mounted on said shaft and the outer end of which rides on a cam 37 on the shaft 38 that is rotated from the crank shaft 4 through a sprocket chain 39 connecting a sprocket wheel 40 on said crank shaft with a similar wheel 41 on the shaft 38. The relative position of the dog and hammer may be varied through an adjusting screw 42 and the impact is obtained for the hammer through the action of a spring 43 that bears one end against said hammer and the other end against check nuts 44 upon a rod 45 that passes through the shank of said hammer and is pivotally secured to the frame 16 by the pintle 46.

100 Assuming now that the port 19, chamber 18 and conductor pipe 21, chamber 8 and port 10 are filled with the combustion fluid, to start the engine the crank shaft 4 is ro-

tated as is usual and through it the shaft 38 and cam 37 whereby the hammer 33 is lifted to its up position, as shown in Figure 1. When the end of the dog 36 5 passes over the notch of said cam, the spring 43 actuates the hammer 33 which strikes a blow upon the head 25 of the plunger, which moves downwardly upon the column of liquid with which it contacts and the 10 sudden impact or blow drives the liquid in the port 10 against the globular valve 13 with sufficient pressure to force the valve off its seat, and at the same time to break up the liquid into small particles, in brief, 15 to atomize it, and by reason of the flaring valve seat 11 and globular valve 13, will cause the same to spread outwardly in a spray or mist over a relatively extensive area and through the spark plug 6 this spray 20 is ignited and the explosion actuates the piston 3 in a well known manner. The then rotation of the crank shaft 4 imparts rotation to the sprocket disk 41 and the shaft 38 and cam 37 are thereafter rotated therewith 25 and successive impacts on the plunger 24 by the hammer 33 produce an intermittent admission of the atomized fluid in the cylinder. During the up stroke of the plunger 24 the check valve 22 is lifted off its seat so as to 30 admit fluid through the inlet pipe 20 and during the down stroke of said plunger the check valve 22 is held on its seat and the check valve 23 is lifted from its seat so as to 35 permit the liquid to pass out of the port 19 into the conductor pipe 21.

In Figure 2, I have illustrated another form of inlet plug wherein the conductor pipe 21 is connected with the plug 9 and a spring 47 surrounds the valve stem 12 and 40 imparts a rotary movement to the fluid as it passes through the port 10 and by reason thereof the spray receives a whirling or centrifugal motion and thereby increases the area of distribution of the spray within 45 the cylinder. In addition thereto, this whirling of the fluid provides an additional force for atomizing it and producing a finer spray.

The admission of fuel into the cylinder of 50 this engine is not effected in any manner by the speed of rotation thereof. In the engines heretofore made the fluid admission into the cylinder is less certain at slow speeds, thus causing skipping if the explosion and stoppage of the engine. Such a 55 result is impossible in this engine, as the impact upon the column of oil is the same irrespective of the slowness of the speed of rotation thereof.

60 The timing of the cam 37 is such that the hammer strikes the head of the plunger as the piston is in its substantially up position.

The adjustment of the dog 36 in relation to the shank of the hammer 33 provides means

whereby the force of the impact of the hammer 65 33 upon the head of the plunger may be varied, as may be desired, to vary the atomization of the fluid and according to the density of the fluid itself.

The details of this mechanism and of its 70 application may be indefinitely varied within the spirit of my invention, which broadly, consists in the use of an impact mechanism for admitting fuel into the cylinder of a combustion engine, and I would therefore 75 have it understood that I do not limit myself to the exact construction herein described and shown in the drawings, but, claim all that falls fairly within the spirit and scope of the appended claims. 80

Having described my invention, what I claim as new and desire to secure by Letters Patent, is:—

1. Means for admitting fluid into the cylinder of an internal combustion engine, 85 comprising in part a member having a discharge stroke, and an impact mechanism for actuating said member for its discharge stroke.

2. Means for admitting fluid into the cylinder of an internal combustion engine, comprising a pump, having a member therein with a discharge stroke, and impact means for actuating said member for its discharge stroke. 90

3. Means for admitting fluid into the cylinder of an internal combustion engine, comprising mechanism that acts upon said fluid through an impact device. 95

4. Means for admitting atomized fluid into the cylinder of an internal combustion engine, comprising in part a member in contact with said fluid, and impact mechanism for imparting movement to said fluid toward said cylinder. 100

5. In a combustion engine, the combination with a valve for the admission of fluid into the cylinder thereof; of means for conducting the fluid to said valve; a member having contact with said fluid; and an impact mechanism associated with said member and providing the force for opening said valve through a shock impulse transmitted through said fluid. 105

6. In a combustion engine, the combination with a valve, having a flaring surface, for the admission of fluid into the cylinder thereof; of means for conducting the fluid to said valve; a member having contact with said fluid; and an impact mechanism associated with said member and providing the force for opening said valve through a shock impulse transmitted through said fluid. 110

7. In a fuel injection mechanism, the combination of an injection valve which opens by applied pressure of fluid fuel, and means to supply fluid fuel to the valve embodying 115

- a fuel pumping element, and impulse mechanism to actuate said pumping element by striking action.
8. In a fuel injection mechanism, the combination of an injection valve which opens by applied pressure of fluid fuel, and means to supply fluid fuel to the valve embodying a fuel pumping element, and impulse mechanism to actuate said element by striking action, and yielding means to vary and control the force of striking action of the impulse mechanism.
9. In a combustion engine, the combination with a valve, for the admission of fluid into the cylinder thereof; of means for conducting the fluid to said valve; a member having contact with said fluid; and a cam controlled impact device associated with said member and providing the force for opening said valve through a shock impulse transmitted through said fluid.
10. In a combustion engine, the combination with a valve, for the admission of fluid into the cylinder thereof; of means for conducting the fluid to said valve; a member having contact with said fluid; an impact mechanism associated with said member and providing the force for opening said valve; a cam, in part controlling the movement of said impact device; and yielding mechanism connected with said valve for resisting the force of said impact device.
11. In a combustion engine, the combination with a valve, for the admission of fluid into the cylinder thereof; of impact actuated mechanism associated therewith and providing the force transmitted through said fluid for opening said valve; and a check valve between the valve first mentioned and said impact mechanism.
12. In a combustion engine, the combination with a valve, for the admission of fluid into the cylinder thereof, of an impact mechanism for opening said valve, comprising a member in contact with said fluid, a hammer, positive means for lifting said hammer; and yielding means for actuating said hammer during its impact movement.
13. In a combustion engine, the combination with a valve for the admission of fluid into the cylinder thereof; of a mechanically centralised, blow actuated impact mechanism for opening said valve; and means for varying the force of said impact.
14. In a combustion engine, the combination with a valve, in its closed position resisting pressure of a column of fluid; of means, initiated by impact mechanism which transmits the force of its blow through said column of fluid, thereby moving said valve off its seat, and means for giving a rotary movement to the fluid in said column adjacent to said valve.
15. In a combustion engine, the combination with the cylinder thereof having a port
- that opens therein and a flaring valve seat at said port opening; of a valve within said port and having a flaring exterior portion; means for holding said valve seated against the fluid column within said port; of a pump for supplying fluid to said column; a member connected with said pump and contacting with said fluid; and a mechanically actuated, impact mechanism for moving said member in one direction.
16. In a combustion engine, the combination with the cylinder thereof having a port that opens therein; of a valve operatively mounted within said port and when closed resisting the pressure of a column of fluid; of a pump for supplying fluid to said column; a plunger within said pump; yielding means for actuating said plunger in one direction; and mechanism for moving said plunger in the opposite direction, said latter mechanism comprising a hammer having an inconstant connection with said plunger, moving in one direction by positively actuated mechanism and in the opposite direction by yielding mechanism.
17. In a combustion engine, the combination with the cylinder thereof, of a piston within said cylinder; a crank shaft; a connection between said crank shaft and piston; an inlet valve in said cylinder when closed resisting the pressure of a column of fluid; impact mechanism for supplying fluid to said column having an inconstant connection with the parts receiving the force of its blow; and means connected with said crank shaft for controlling the movement of said impact mechanism in one direction.
18. The combination with a pump having a member therein mounted so as to have a discharge and suction movement, of means for actuating said member in one direction, comprising impact mechanism mounted and actuated so as to deliver a blow to said member and when in its rest position out of contact therewith, a distance from said member.
19. The combination with a pump having a member therein mounted so as to have a discharge and suction movement, of means for actuating said member in one direction, comprising impact mechanism mounted upon one side of said member and which in one of its positions is at a point distant from said member and out of contact therewith.
20. The combination with a pump having a member therein mounted so as to have a discharge and suction movement, of means for actuating said member in one direction, comprising an element set in motion prior to its contact with said member, whereby said member receives a shock impulse for its initial movement.
21. The combination with a pump having a member therein mounted so as to have a discharge and suction movement, of means

- 4
- for actuating said member in one direction, said means comprising a weighted element mounted so as to be moved toward and away from said member and actuated so as to acquire momentum before it engages said member, whereby said member receives a shock impulse for its initial movement.
22. In a combustion engine, the combination with the cylinder thereof having a port 10 that opens therein; of a valve operatively mounted within said port and when closed resisting the pressure of a column of fluid; of a pump for supplying the fluid to said column; a plunger within 15 said pump; yielding means for actuating said plunger in one direction; an impact mechanism for moving said plunger in the opposite direction, said latter mechanism comprising a hammer moving in one direction by positively actuated mechanism and in the opposite direction by yielding mechanism; and means for limiting the movement of said plunger in one direction.
23. In a combustion engine, the combination with the cylinder thereof having a port 25 that opens therein; of a valve operatively mounted within said port and when closed resisting the pressure of a column of fluid; of a pump for supplying the fluid to said column; a plunger within said pump; yielding means for actuating said plunger in one direction; an impact mechanism for moving said plunger in the opposite direction; said latter mechanism comprising a hammer moving in one direction by positively actuated mechanism; and adjustable means for limiting the outward movement of said plunger.
24. In a combustion engine, the combination with the cylinder thereof; of an inlet 40 port for admitting fluid to said cylinder; a valve mounted within said port and when closed resisting the pressure of a column of fluid; an impact mechanism for admitting fluid to said column and through it to the interior of said cylinder, said impact mechanism comprising a hammer, a rotary cam, a dog between said hammer and cam whereby movement is imparted from said cam to said hammer; and spring means for moving said hammer in one direction whereby the impact force of said hammer is obtained by said yielding mechanism when said dog passes over a notch on said cam.
25. In a combustion engine, the combination with the cylinder thereof; of an inlet 55 port for admitting fluid to said cylinder; a valve mounted within said port and when closed resisting the pressure of a column of fluid; an impact mechanism for admitting fluid to said column and through it to the 60 interior of said cylinder, said impact mechanism comprising a hammer, a rotary cam, a dog between said hammer and cam whereby movement is imparted from said cam to said hammer; a spring having engagement with said hammer and exercising its tension so as to maintain said dog in contact with said cam and causing said hammer to strike its blow when said dog passes over a notch on said cam.
26. In a combustion engine, the combination with the cylinder thereof, of a piston operatively mounted therein; a crank shaft; a connection between said piston and crank shaft; a pump; a conductor pipe between said pump and cylinder; a valve for controlling the supply of fluid to said cylinder; a plunger in said pump; a rotary shaft; an operative connection between said shafts; a 70 cam on said rotary shaft; a pivotally mounted hammer; a dog connected with said hammer contacting with said cam; and a spring engaging said hammer for moving the same when not actuated by said cam.
27. In a combustion engine, the combination with the cylinder thereof, of a piston operatively mounted therein; a crank shaft; a connection between said piston and crank shaft; a pump; a conductor pipe between said pump and cylinder; a valve for controlling the supply of fluid to said cylinder; a plunger in said pump; and an impact mechanism, intermittently actuated from said crank shaft for operating said plunger and applying pressure to the fluid in said conductor pipe.
28. In a combustion engine, the combination with a member having a flaring valve seat therein; of a valve having a globular portion, which contacts with said valve seat at a single point in a uniform plane, whereby the open space between said valve and its seat, except at their contact points, increases in width as it approaches the stem of said valve; means for admitting fluid to said open space; and impact mechanism for moving said valve off its seat, forcing said fluid between it and said valve seat.
29. Means for admitting fluid into the cylinder of an internal combustion engine at predetermined periods through the action of impact mechanism whereby a shock impulse is imparted to said fluid.
30. In a fuel injection mechanism, a fuel pumping element, impulse mechanism to actuate said element by striking action, and means to control and vary the force of said striking action.
- In testimony whereof I have hereunto affixed my signature.
- STEPHEN A. HASBROUCK.
